ELECTRIC DISCHARGE TUBE

Orrick Howard Biggs, Beverly, Mass., assignor to
 Hygrade Sylvania Corporation, Salem, Mass.,
 a corporation of Massachusetts

Application November 17, 1934, Serial No. 753,424

6 Claims. (Cl. 250—27.5)

This invention relates to electric discharge tubes and with particularity to devices having transparent enclosing envelopes such as lamps, cathode-ray-tubes, radio tubes or the like.

5 In certain types of discharge devices particularly in those employing one or more electron emitters, it has been known that the interior surface wall of the enclosing vessel or envelope tends to accumulate an electrostatic charge which in 10 many cases interferes with the starting or proper functioning of the device. This phenomenon is particularly pronounced in those devices where the enclosing envelope is of a tubular or elongated shape, for example cathode-ray-tubes, gaseous discharge lamps and the like. Various devices 15 have been proposed heretofore for dissipating this unwanted wall charge. For example it has been proposed to seal into the tube wall one or more metal members to conduct away the charges. 20 Another proposal has been to surround the tube with a conducting shield or cage, while a still further proposal has been to coat the inner surface of the tube with a conductive material such as graphite or metal. Entirely apart from the cost 25 of incorporating these special conductive devices is the fact that the opacity of the conducting members or coatings renders them objectionable when applied to lamps, cathode-ray-tubes or the like where light transmission efficiency is the desideratum.

Accordingly one of the principal objects of this invention is to provide a lamp, tube or similar device with a substantially transparent enclosing envelope which is relatively free from wall charge 35 effects.

A feature of the invention relates to a lamp or tube having one or more electrodes enclosed within a transparent envelope which is treated to render it inherently conducting without substantially affecting its transparency.

Another feature of the invention relates to a discharge lamp or tube with a substantially transparent vitreous envelope having incorporated in the body thereof a conductive material or materials.

Another feature relates to a discharge tube or lamp having a substantially transparent vitreous envelope having incorporated therein a conductive metallic salt.

50 Other features and advantages not specifically enumerated will be apparent after a consideration of the following detailed description and the appended claims.

While the invention will be described herein as 55 embodied in a typical form of cathode-ray-tube

and a gaseous discharge lamp, it will be understood that this is done merely for purposes of illustration and not by way of limitation.

In the drawing Fig. 1 illustrates schematically in sectional view a typical form of cathode-ray- 5 tube embodying features of the invention.

Fig. 2 illustrates diagrammatically the invention as embodied in a gaseous discharge lamp.

Referring more particularly to Fig. 1 there is shown a cathode-ray-tube having a vitreous 10 envelope comprising a cylindrical neck portion 1, a conical body portion 2 and a flattened end wall 3. The neck portion 1 has sealed thereto a re-entrant stem 4 terminating in a press 5 through which certain of the lead-in wires pass. Suitably 15 mounted within the tube is a heater 6; an electron emitting cathode 7; a control electrode 8; a focusing electrode 9; an anode 10 and deflecting plates 11. For a more detailed description of a tube of this character, reference may be had to copending 20 application Serial No. 724,878, filed May 10, 1934.

In accordance with the usual practice the interior surface of the end wall 3 is provided with a coating which fluoresces under the impact of the cathode rays. The electrons emitted from the 25 cathode 7 pass through the opening in the control electrode 8 and thence through the openings in the focusing electrode 9 and the anode 10. By means of suitably variable potentials applied to the deflecting plates 11 the cathode-ray-beam 30 is oscillated to trace a desired pattern on the screen 12. Unless particular precautions are taken the stray electrons which strike the inner surface of the vitreous tube produce an electro- 35 static charge on this surface which charge tends to reduce the velocity of the electrons in the main cathode beam, and tending also to reduce the brightness of the spot on the screen 12. The existence of this electrostatic charge also tends to destroy the focus of the cathode beam result- 40 ing in a blurred spot on the screen. In order to prevent the formation of this electrostatic charge the glass or vitreous material constituting the enclosing envelope has incorporated therein a material or materials which impart the desired 45 conductivity to the tube wall. As examples of such materials may be mentioned metallic conductive salts such as stannous chloride, ferric chloride or the like. These conductive materials or salts may be incorporated in the vitreous envelope in any well-known manner, for example the stannous chloride may be fused into the body of the glass at approximately about 500° C. This material imparts a slight iridescence to the glass 50

55

but does not materially effect its light transmission power.

It will be understood of course that it is necessary, in connection with the tube of Fig. 1, to impart this conductivity to only that portion of the tube where the wall charge effects tend to exist or be deleterious. For example the cylindrical neck portion 1 and the stem 4 may be of glass such as is ordinarily employed in lamps, 10 tubes or the like, whereas the conical portion 2 and the wall portion 3 may have incorporated therein the conductive materials mentioned. Consequently when the tube of Fig. 1 is in actual use any wall charge that tends to accumulate is 15 immediately conducted away. If desired the conductive portion 2 of the tube may be connected to ground or to a suitable base potential to facilitate the dissipation of the charge.

Referring to Fig. 2 there is shown in schematic 20 form a typical gas discharge lamp with a tubular envelope comprising a main body portion 13 and end or seal-in portions 14 and 15. Portions 13 and 14 are fused or otherwise hermetically joined together at the points 16, 17. Sealed into the 25 portion 14 is a suitable electrode 18 and a similar electrode 19 is sealed into the portion 15. To facilitate the sealing, suitable beads 20 and 21 of specially chosen glass may be employed if desired. The sealed tube is previously evacuated and then filled with an ionizable medium such 30 as an inert gas, mercury vapor or any desired mixture of these. Preferably, although not necessarily, the electrodes provided with electron emissive coatings such as an alkaline earth oxide 35 or a mixture of alkaline earth oxides, as for example are used in the radio tube art. When the electrodes 18 and 19 are connected in circuit with a suitable source of potential, the ionized discharge through the tube causes a bombardment 40 of one or the other of the electrodes. The gas pressure and voltage may be so chosen that the bombardment is sufficient to raise one of the electrodes to a temperature at which it becomes thermionically emissive. It will be understood of 45 course that the invention is not limited to the bombardment method of heating one or both of the electrodes, and that any well known method of heating the electrodes to render them electronically emissive may be employed. It has been 50 found that when the tubular portion 13 of the enclosing envelope has incorporated therein a specially chosen material or materials, the envelope wall becomes sufficiently conductive to prevent the accumulation of an electrostatic charge

which would otherwise interfere with the proper starting or operation of the lamp. As examples of these materials which impart the desired conductivity to the envelope wall without substantially affecting the light transmission characteristics of the said wall may be mentioned stannous chloride, ferric chloride or a mixture thereof. 5

Various changes and modifications may be made herein without departing from the spirit and scope of the invention. For example while 10 it is preferred to incorporate the conductivity-imparting materials in the body of the vitreous envelope, these materials may be glazed on to the envelope in any well known manner. Furthermore, while certain specific materials have 15 been mentioned herein, it will be understood that other similar materials may be incorporated so long as these materials do not materially interfere with the light transmission characteristics of the envelope nor deleteriously affect the life or 20 operating characteristics of the lamp or tube. The term gaseous discharge as employed herein is intended to include a discharge through a vapor as well as a discharge through a gas.

What I claim is:

1. A space discharge device comprising a pair 25 of electrodes one of which is adapted to emit electrons, a transparent enclosing envelope for said electrodes, said envelope having a selected portion of its wall normally conductive vitreous 30 material.

2. A space discharge device comprising an electron emitting cathode, an anode, an elongated enclosing envelope for said cathode and anode, said envelope having a transparent wall of nor 35 mally conductive vitreous material.

3. A space discharge device comprising an electron emitting cathode, an anode for said cathode, a transparent envelope enclosing said electrodes, said envelope having incorporated therein a quantity of a metallic chloride to impart conductivity 40 to said envelope without substantially affecting the transparency of said envelope.

4. The combination according to claim 3, in which the chloride is stannous chloride. 45

5. The combination according to claim 3, in which the chloride is ferric chloride.

6. A gaseous discharge lamp comprising a pair of spaced electrodes between which a visible discharge is to be produced, and a vitreous tubular 50 envelope enclosing said electrodes having a selected portion of the envelope wall of normally conductive transparent vitreous material.

ORRICK H. BIGGS.
